(57) **CLAIM**

The ornamental design for a signaling device, as shown and described.

DESCRIPTION

FIG. 1 is a perspective view of the front of the signaling device in a vertical position.

FIG. 2 is perspective view of the front and bottom of the signaling device in a horizontal position.

FIG. 3 is a perspective view of the back of the signaling device in a vertical position.

FIG. 4 is a top orthogonal view of the signaling device.

FIG. 5 is a front orthogonal view of the signaling device.

FIG. 6 is a right side orthogonal view of the signaling device. Both sides are symmetrical

FIG. 7 is a back orthogonal view of the signaling device; and,

FIG. 8 is a bottom orthogonal view of the signaling device. The broken line showing is for illustrative purposes only and forms no part of the claimed design.
